United States Patent Office

Des. 207,451
Patented Apr. 18, 1967

207,451

DIGGER TOOTH

William W. Wilson, 6204 W. Canal Blvd.,
Shreveport, La. 71108

Filed Aug. 3, 1966, Ser. No. 3,327

Term of patent 14 years

(Cl. D39—1)

FIG. 1 is a perspective view of a digger tooth showing my new design,

FIG. 2 is a bottom plan view thereof;

FIG. 3 is a side elevation thereof;

FIG. 4 is a rear elevation looking in the direction of line 4—4 of FIG. 1; and

FIG. 5 is a front elevation looking in the direction of line 5—5 of FIG. 2.

I claim:

The ornamental design for a digger tooth, as shown.
